UNITED STATES PATENT OFFICE.

JAMES A. STREET, OF DETROIT, MICHIGAN, ASSIGNOR OF ONE-HALF TO HUGO C. ZEITZ, OF CLARKSBURG, WEST VIRGINIA.

TOOL HOLDING AND DRIVING MECHANISM.

Application filed October 30, 1922. Serial No. 597,713.

To all whom it may concern:

Be it known that I, JAMES A. STREET, a citizen of the United States, residing at Detroit, county of Wayne, State of Michigan, have invented a certain new and useful Improvement in Tool Holding and Driving Mechanism, and declare the following to be a full, clear, and exact description of the same, such as will enable others skilled in the art to which it pertains to make and use the same, reference being had to the accompanying drawings, which form a part of this specification.

My invention relates to improved tool-holding and driving mechanism of simple, sturdy construction. An object is to provide improved tool-holding and driving mechanism of simple, sturdy, efficient design which is so constructed that in tapping, drilling, bolting, stud setting or other operations the tool-holding portion of the mechanism may be released from the driving power when the imposition of resistance to the rotation of the tool approaches the danger point.

It is well known that in such operations tools are frequently broken due to a sudden increase in restraint of rotation; reamers do not line up with the aperture to be reamed and breakage is the result, and in multiple working increase in downward pressure upon certain of the tools due to the completion of the operations by certain other tools in the series frequently causes tools upon which the pressure is increased to break under the strain.

My invention comprises an improved construction which permits release of the tool from the driving force upon dangerous increase of resistance to rotation and continued overrunning by the driving member of the driven tool-holding member during the stoppage thereof, operable, however, to automatically re-engage said members for rotation upon reversal of the relative rotation of said members.

The above and other objects, together with particular features of construction, will more fully appear from the following description, appended claims and accompanying drawings, in which my invention is shown as embodied in connection with a tool-holding chuck, though it is apparent that the release mechanism might be incor-

porated between driving and driven spindles at any point desired.

In the drawings,—

Figure 1 is a side elevation of my improved chock, partly broken away.

Fig. 2 is a vertical section through the barrel portion of the chock taken on line II—II, of Fig. 2.

Fig. 3 is a cross-sectional view taken on the line III—III of Fig. 2.

Fig. 4 is a cross-sectional view taken on the line IV—IV, of Fig. 2.

Fig. 5 is a perspective of one of the cam levers 42.

Fig. 6 is a perspective of one of the vertically movable cams 46.

Fig. 7 is a broken away vertical sectional view through the barrel.

Fig. 8 is a sectional view taken on the same line as Fig. 3 showing the tool-holding member and driving member coupled together for driving.

Fig. 9 is a sectional view taken on the line 9—9 of Fig. 8.

Fig. 10 is a vertical sectional view taken on the line 10—10 of Fig. 11.

Fig. 11 is a horizontal sectional view through a modified form of my device taken on the same line as Fig. 3.

Fig. 12 is a perspective of a slidable cam.

My improved tool comprises a driving member and a driven tool-holding member adapted to be releasably coupled with said driving member to rotate therewith but which coupling is of such a character as to permit said driving member to rotate independently of the tool-holding member when the rotation of the tool is obstructed to such a degree as to approach the danger point of breakage thereof.

In the drawings, let 20 indicate the driving member provided with a suitable shank and having an enlarged head 21 which is provided with an exterior shoulder 22 that serves as a support for a ball race 23, upon one member of which race is threaded a barrel 24. It will be seen, therefore, that the driving member has a rotation relative to the barrel and the barrel is so formed at the lower end as to receive a tool-holding socket 25 which is secured to the barrel by means of a suitable pivot pin 26 so as to provide for limited floating movement of the socket and carried tool relative the bar-

rel. The lower portion of the socket is adapted to removably receive a tool, not shown in the drawing. So as to yieldingly preserve the vertical alinement of the tool and socket relative each other, I provide spiral springs 27 and 28, which, however, are, as will be seen, yieldable to permit pivotal movement of the tool socket so that the tool may be driven though it is not alined axially with the driving member.

The head 21 of the driving member is diametrically recessed as at 29, which diametrical recess is provided with an axial recess 30. I provide a driving head 31 having a diametrically arranged portion 32 which is disposed within the diametrical recess 29 in the head 21 and the portion 32 is provided with a stem 33 receivable within the recess 30 in the head 21. Surrounding the stem 33 is a spring 34 which exerts downward pressure on the driving head 31. As shown in Fig. 2, I have provided a plurality of springs 34 bearing downwardly on the driving head. It is obvious that such a number of these springs might be provided as was found most suitable for the purpose.

Positioned in the bottom of the barrel is a bearing plate 35, which is shown as locked to the barrel by means of a set screw 36 to rotate with the barrel. I provide means to releasably lock the driving head 31 to the bearing plate 35 to produce rotation thereof as follows: The driving head 31 is provided with a pair of opposed rollers or couplers 37 which are supported upon spindles 38 so as to depend below the lower face of the driving head. These rollers are adapted to engage in opposite ends of a diametrical recess 39 formed in the bearing plate 35 to produce rotation of the bearing plate as one piece with the driving head 31. Mounted in this recess 39 are two slidably disposed blocks 40 held outwardly therein by means of a spiral spring 41, the upper surfaces of which blocks lie flush with the upper surface of the bearing plate 35. Pivoted to each block is a cam lever 42 which is secured to the bearing plate by means of a vertical stud 43 which travels in a slot 44 in the lever. Each lever is beveled at the free end as at 45 for a purpose hereinafter described. The normal position of the blocks and levers is shown in Fig. 3, in which the blocks are held outwardly in the recess so as to prevent engagement of the rollers therein as they travel over the face of the plate 35.

The driving head 31 carries in addition to the rollers 37 a pair of vertically movable cam members 46 shown in perspective in Fig. 6. These cams are disposed in vertical openings extending through the driving head which are shaped to receive the cam and each cam is provided with a flange 47 which rests upon the upper surface of the driving head. Each cam is held downward-

ly by means of a spring 48, one end of which engages the lower end of the head 21 and the other end of the spring is received over a stud 49 formed on the upper end of the cam 46. The cams are narrowed to an edge 50 at one end as at 50 and the opposite end of the cam is beveled as at 51. In the forward movement of the driving member when disengaged from the plate 35, and the blocks 40 are held outwardly by means of the spring 41, these cams 46 travel up over the cam levers 42, the beveled end 51 of the cam riding up over the beveled end 45 of the lever and the cam yielding vertically upwardly against the resistance of its spring 48. This is the movement which occurs when the rotation of the working tool is impeded and the driving member is rotated independently of the tool, or as shown in Fig. 3, in which the cams and rollers appear in dotted outline.

Upon reversal of the rotation of the driving member the edge 50 of the cam engages the side of the lever 42 in such a manner that the two cams tend to force the levers in the direction shown in Fig. 8 so that the blocks 40 are withdrawn against the resistance of the spring 41, opening the opposite ends of the passageway 39 so that continued rotation of the driving head brings the rollers 37 into position to fall within this recess engaging the bearing plate 35 for rotation with the driving head. The position of the cams and levers is then as indicated in Fig. 8 and the tool is in the operative position.

In Figs. 10, 11 and 12, I have shown a modified form of construction in that instead of the cams 46 engaging the two levers 42, these cams engage a single slidable block 50 beveled as shown in Fig. 12, which block is provided with a base plate 51 disposed within a radial recess formed in the bearing plate 35 for reciprocal radial movement therein. It is held outwardly by means of a spring 52 but the extent of outward movement is limited by a stop 53 carried by the plate 35 which extends upwardly in a slot 54 formed in the base plate. This block 50 has two angularly disposed faces which intersect at a point 55 that is disposed between the ends of the levers 42. These levers are pivoted to the blocks 40 as heretofore set forth but project outwardly in a different fashion so that each lever is acted upon by the block 50 at the same time and inward movement of the block 50 spreads the outer ends of the levers apart and brings the inner ends together withdrawing the blocks 40 against the tension of the spring 41 to permit the rollers to engage in the recess 39.

When the driving head is locked to the bearing plate 35 it will be seen that the tool may be rotated as desired but that when the tool strikes an obstruction, producing suffi-

cient resistance to its rotation, release of the rollers from the recess 39 will automatically occur, the springs 34 yielding to permit such release, and the driving head will rotate independently, overrunning the tool-holding portion of the device, and this will continue to take place as above set forth until the direction of rotation of the driving member is reversed, at which time the action of the cams as above described will retract the blocks 40 so as to permit the rollers to engage in the recess in the bearing plate, withdrawing the tool and permitting reversal of rotation to again operate the tool in the forward direction.

What I claim is:

1. In a device of the class described, in combination, a driving member, a driven tool-holding member, rollers carried by one member held under spring pressure to engage said other member to cause said members to rotate as one piece and releasable to permit independent overrunning rotation of said driven member by said driving member upon imposition of resistance to rotation upon said driven member sufficient to overcome the spring pressure on said rollers, and means operable to prevent re-engagement of said rollers during said overrunning rotation.

2. In a device of the class described, in combination, a driving member, a driven tool-holding member, rollers carried by one member held under spring pressure to engage said other member to cause said members to rotate as one piece in the forward direction and releasable to permit said driving member to rotate independently of said driven member in such forward direction upon imposition of resistance to rotation upon said driven member sufficient to overcome said spring pressure and effect release of said rollers from driving engagement, and means automatically operable to prevent re-engagement of said rollers during the independent forward rotation of said driving member, said means further operable upon reversal of rotation of said driving member to permit re-engagement of said rollers to pick up said driven member for rotation.

3. In a device of the class described, in combination, a driving member, a driven tool-holding member, rollers carried by one of said members, a bearing plate for said rollers carried by said other member provided with depressions within which said rollers may engage to couple said members together to rotate as one piece, spring means holding said rollers under pressure to engage in said depressions yieldable under imposition of a determined resistance to rotation upon said tool-holding member to permit disengagement of said rollers from said depressions, and means operable to pre-

vent re-engagement of said rollers in said depressions during the continuance of rotation of said driving member.

4. In a device of the class described, in combination, a driving member, a driven tool-holding member, rollers carried by one of said members, a bearing plate for said rollers carried by said other member provided with depressions within which said rollers may engage to couple said members together to rotate as one piece in the forward direction, spring means holding said rollers under pressure to engage in said depressions yieldable to permit disengagement of said rollers from said depressions to permit independent rotation of said driving member in such forward direction, and means automatically operable to prevent re-engagement of said rollers in said depressions during the continued forward rotation of said driving member operable to permit such re-engagement upon reversal of rotation of said driving member.

5. In a device of the class described, in combination, a driving member, a driven tool-holding member, rollers carried by one of said members, a bearing plate for said rollers carried by said other member provided with depressions within which said rollers may engage to couple said members together to rotate as one piece in the forward direction, spring means holding said rollers under pressure to engage in said depressions, spring-controlled means operable to prevent re-engagement of said rollers in said depressions during the continued forward rotation of said driving member.

6. In a device of the class described, in combination, a driving member, a driven tool-holding member, rollers carried by one of said members, a bearing plate for said rollers carried by said other member provided with depressions within which said rollers may engage to couple said members together to rotate as one piece in the forward direction, spring means holding said rollers under pressure to engage in said depressions, spring-controlled means operable to prevent re-engagement of said rollers in said depressions during the continued forward rotation of said driving member releasable to permit such re-engagement upon reversal of rotation of said driving member.

7. In a device of the class described, in combination, a driving member, a driven tool-holding member, a coupling device carried by one of said members, said other member provided with a plate having a transverse recess in which said coupling device may engage to produce rotation of said driving and driven members as one piece, spring means holding said coupling device under pressure to engage in said recess yieldable to permit disengagement of said device therefrom, slidably arranged blocks
